MSATTORNEY.

UNITED STATES PATENT OFFICE

OSCAR P. ANDERSON, OF AURORA, ILLINOIS

TEMPERING MACHINE

Application filed October 17, 1930. Serial No. 489,440.

This invention relates to certain novel improvements in tempering machines, and has for its principal object the provision of an improved construction of this character which will be highly efficient in use and economical in manufacture.

The salient object of this invention is the provision of an improved machine for tempering springs.

A further object of the invention, ancillary to the foregoing object is the provision of an improved machine for tempering coil springs.

An additional object of the invention is the provision of an improved construction for tempering springs with oil and which is particularly adapted for tempering coil springs such as are used on railroad cars and the like.

Other objects will appear hereinafter.

The invention consists in the novel combination and arrangement of parts to be hereinafter described and claimed.

The invention will be best understood by reference to the accompanying drawings, showing the preferred form of construction and in which:

Fig. 1 is a side elevational view partly in section of a preferred form of construction of the invention;

Fig. 2 is a fragmentary side elevational view showing a part of the machine illustrated in Fig. 1;

Fig. 3 is a sectional view taken substantially on the line 3—3 in Fig. 1;

Fig. 4 is a sectional view taken substantially on the line 4—4 in Fig. 1;

Fig. 5 is a sectional view taken substantially on the line 5—5 in Fig. 1; and

Fig. 6 is a perspective view of certain units embodied in the invention.

Referring to the drawings wherein a preferred embodiment of my invention is illustrated, 10 indicates a tank or housing for containing any suitable tempering oil. An inlet connection 11 is attached to the tank 10 by means of suitable connecting elements such as the bolt and nut constructions 12 and 13 and provided in the inlet connection 11 is a pump 14 of any approved type. An outlet connection 15 is provided adjacent the bottom

of the tank 10 and suitable cooling coils (not shown) are connected between the inlet 11 and the outlet 15 so that the oil in the tank 10 may be circulated therethrough and properly cooled.

A table 16 is provided at one end of the tank 10 at the top thereof and the table is connected to flanges 40 and 41 provided on the side portions of the tank 10 at the upper side thereof and to a flange 17 provided at one end of the tank 10 by means of suitable connecting elements such as the bolt and nut constructions 18 and 19. As best shown in Fig. 1, the table 16 extends across a portion of the tank 10 at the top and adjacent one end thereof for a purpose to be described hereinafter.

Extending from the inner end of the table 16 to the opposite end of the tank 10 is a hood 21 which covers a wheel 22, the construction of which will be described presently. The hood 21 includes flange portions 47 and 48 which are secured by means of suitable connecting elements such as the bolt and nut constructions 49 to the flange portions 40 and 41 provided on the side walls of the tank 10. The wheel 22 carries a plurality of pivotally mounted baskets 23. An inlet opening 24 is provided in the end portion 50 of the hood 21 at the end adjacent the table 16 and a discharge opening 25 is provided opposite end portion 51 of the hood.

In the operation of my invention, coil springs 26 are elevated on to the table 16 and rolled forwardly therein through the opening 24 in the hood and thence into the baskets 23 as the wheel 22 is revolved on its shaft through suitable gears 28 and 29 and a driving shaft 30 which is connected to a suitable source of power. As the wheel 22 revolves at a predetermined speed the springs 26 are carried in the baskets 23 through the tempering oil contained in the tank 10. The wheel 22 is rotated in a clockwise direction, as viewed in Fig. 1, and as the baskets 33 containing the springs 26 are rotated through the tank 10 the baskets 23 are dumped individually by means of a resilient trip 31 which is mounted in the end wall 22 of the tank 10 by means of rivets 32 or the like. The springs 26 are rolled on to a sliding shelf 39 of a discharge table 32

and from the table 32 into a suitable receptacle provided therebelow but not shown. It is apparent that as the heated springs 26 are carried through the oil in the tank 10 the oil will become heated and gases be given off.

5 To allow for the escape of such gases I provide an outlet connection 33 in the hood 21 and this connection includes a flanged base 34 which may be secured to the hood in any 10 approved manner such as by welding.

The shaft 27 is journaled in bearings 35 and 36 which are secured by means of bolt and nut constructions 38 and 39 to flanged portions 40 and 41 formed on the sides of the 15 tank 10 at the top thereof. Carried by the shaft 27 and keyed thereto by means of pins 42 and 43 are hubs 44 and 45. Provided on the shaft 27 and keyed thereto by means of pins 52 are spacing collars 53 and 54.

10 Extending radially from the hub 44 at predetermined intervals is a plurality of spokes 55 which include flange portions 56 and these flange portions are secured to the hub 44 by means of suitable connecting elements such 15 as rivets 57. Similar and aligned spokes 58 radiate from the hub 45 and these spokes include similar flanges 59 which are secured to the hub 45 by means of rivets 60 or the like. Connecting links 61 are provided between the 20 spokes 55 and secured thereto by means of rivets 62 or the like. Similar connecting links are provided between the spokes 58. Extending between each pair of aligned 25 spokes 55 and 58 are cross braces 63 which are connected to the spokes 55 by means of rivets 64 or the like and to the spokes 58 by means of rivets 65 or the like. Extending between each aligned pair of spokes 55 and 58 are 30 braces 66 which are secured to the spokes 55 by means of rivets 67 or the like and to the spokes 58 by means of rivets 68 or the like.

The baskets 23 include ear portions 69 and 70 in which are provided openings 71 and 72. A block 73 is provided on each of the spokes 55 and a similar block 74 is disposed on each of the spokes 58. Formed in the blocks 73 and 74 are openings 75 and 76 and aligned with these openings are similar openings 77 and 78 in the spokes 55 and 58, respectively. 35 In mounting the baskets 23 for pivotal movement a suitable connecting element such as threaded bolt 79 is inserted through each of the ear portions 70 of the baskets so as to allow the basket 23 to swing thereon. As shown in Fig. 6, a similar bolt 80 is inserted through the opening 71 in the ear 69, through each of the openings 78 in the spokes 58, through the opening 76 in the block 74. Suitable nuts (not shown) are provided on the threaded portions of the bolts 79 and 80 40 interiorly of the blocks 73 and 74. It is

manifest, therefore, that the baskets 23 are mounted for swinging movement on the bolts 79 and 80. A plurality of spaced apart openings 81 are provided in the baskets 23 so that oil may drain therefrom as the baskets are 70 rotated upwardly of the trip 31.

The shelf plate 89 includes arm portions 82 and 83 in which slots 84 and 85 are provided and similar slots are provided in the table 32. As in Figs. 1 and 5, the shelf plate 75 89 is adjustably mounted for sliding movement on the discharge table 32 by means of suitable bolt and nut constructions 86 and 87 which are inserted in the slots 84 and 85. By referring to Fig. 5 it may be seen, therefore, 80 that the shelf 89 may be adjusted so as to project into the hood 21 any desired distance.

The table 32 is mounted on the end wall 9 of the tank 10 by means of a downwardly depending portion 96 and rivets 97 or the like. The outer end of the table 32 is supported on a housing 90 which provides a trough 94 and this housing may be secured to the end wall 22 in any approved manner such as by welding. The table 32 includes upstanding flange portions 91 and 92 to provide guides for the springs 26 as the springs roll off the table 32. A plurality of openings 93 are provided in the table 32 to permit drainage of oil from the springs therethrough into the trough 94 95 and thence into the tank 10 through an opening 95 provided in the end wall 22. An offset portion 98 is provided in the housing 90 and a screen 99 is mounted on this offset portion 98 and secured to the portion 96 in any 100 approved manner. It will be apparent, therefore, that oil carried by the springs 26 on to the shelf 89 and table 32 will drain through the openings 93, through the screen 99 into the trough 94 and thence into the tank 10 105 through the opening 95.

A suitable source of power such as an electric motor is connected to the shaft 30 in any approved manner and it is manifest that as the shaft 30 is rotated the gear 27 thereon will drive gear 28 and shaft 27. A suitable timing device not shown, may be provided for rotating the wheel 22 and attached baskets 23 at any desired speed which is dependent on the material of which the springs to be tempered are made, the heat imparted thereto in the heating operation preceding tempering, the kind of oil used, etc., as is well understood in the art.

It is manifest, therefore, that as the wheel 22 is rotated and the springs 26 such as for example the coil springs used on railway cars, are elevated onto the table 16, these springs may be rolled through the opening 24 in the hood into the baskets 23 and it will be seen that as the baskets 23 are rotated clockwise on the wheel 22 they move the springs 26 through the oil in the tank 10 at a rate of speed which can be determined to suit the needs of conditions. As the baskets 23 and 120

springs 26 held therein are rotated upwardly the baskets are selectively dumped by the trip 31, as best shown in Fig. 2, thereby allowing the springs 26 to roll out onto the inclined shelf 89 and thence over the table 32 and into a suitable receptacle (not shown) which may be provided below the lower end of table 32.

From the foregoing description of my invention it is manifest that I have provided 10 an improved machine for tempering coil springs and the like which while effectively accomplishing its other objects as pointed out hereinbefore will be simple and economical in construction and highly efficient in use.

15 While I have illustrated and described the preferred form of construction for carrying my invention into effect, this is capable of variation and modification, without departing from the spirit of the invention. I, therefore, do not wish to be limited to the 20 precise details of construction set forth, but desire to avail myself of such variations and modifications as come within the scope of the appended claims.

25 Having thus described my invention what I claim as new and desire to protect by Letters Patent is:

1. A machine of the class described including a housing providing a tank adapted to 30 contain a liquid and providing a hood over said tank, a wheel mounted for rotatable movement through said tank and said hood, supporting means for said wheel including a rotatable shaft member, a plurality of baskets mounted for swinging movement on said wheel and rotatable therewith, means for pivotally mounting said baskets on said wheel, a table supported on said tank at the upper side of said tank and adjacent one end thereof, means for securing said table on said tank, said hood having an opening therein adjacent the inner end of said table whereby material may be fed from said table into said baskets, means connected to said shaft for operating 40 said wheel whereby material in said baskets may be rotated through said liquid, and means for discharging material from said baskets out of said housing.

2. A machine of the class described including a housing providing a tank adapted to 50 contain a liquid and providing a hood over said tank, a wheel mounted for rotatable movement through said tank and said hood, supporting means for said wheel including a rotatable shaft member, a plurality of baskets mounted for swinging movement on said wheel and rotatable therewith, means for pivotally mounting said baskets on said wheel, a table supported on said tank at the upper 55 side of said tank and adjacent one end thereof, means for securing said table on said tank, said hood having an opening therein adjacent the inner end of said table whereby material may be fed from said table into said baskets, means connected to said shaft for operating 60 said wheel whereby material in said baskets

said wheel whereby material in said baskets may be rotated through said liquid, said housing having an outlet opening therein at the end opposite said table, a trip mounted 70 interiorly of said housing below said outlet opening, a table mounted on said housing below said last-named opening including a 75 slideable shelf projecting into said housing through said opening, whereby when said wheel and attached baskets are rotated through said liquid said baskets will successively engage said trip to dump said baskets and to discharge material therefrom onto said last-named table.

3. A machine of the class described includ- 80 ing a housing providing a tank having inlet and outlet connections therein adapted to contain a liquid and providing a hood having a vent in the upper wall thereof, a wheel mounted for rotatable movement through 85 said tank and said hood and including a plurality of radially extending spokes arranged in oppositely disposed rows and aligned in pairs, a shaft member rotatably mounted in said housing, means providing connection be- 90 tween said shaft member and said spokes, bracing means for said spokes, a plurality of baskets mounted for swinging movement between each of said pairs of spokes, means providing pivotal connection between said bas- 95 kets and said spokes, a table mounted on said tank adjacent one end thereof, securing means for said table, said hood having an inlet opening formed therein substantially at the level of said table and having an outlet opening 100 formed therein opposite said inlet opening, a trip mounted on said tank interiorly there- 105 of and below said outlet opening, a table mounted on said tank and including a slideable shelf member adapted to project through said outlet opening, this construction being such that material may be discharged from said first-named table into said baskets and carried through said liquid to said trip to be discharged from said baskets onto said shelf and 110 said last mentioned table.

4. A machine of the class described includ- 115 ing a housing providing a tank adapted to contain a liquid and providing a hood over said tank, a wheel mounted for rotatable movement through said tank and said hood, supporting means for said wheel including a rotatable shaft member, a plurality of baskets having discharge openings provided therein, mounted for swinging movement on said 120 wheel and rotatable therewith, means for pivotally mounting said baskets on said wheel, a table supported on said tank at the upper side of said tank and adjacent one end thereof, means for securing said table on said tank, said hood having an opening therein adjacent the inner end of said table whereby material may be fed from said table into said 125 baskets, means connected to said shaft for operating said wheel whereby material in said 130

baskets may be rotated through said liquid, and means for discharging material from said baskets out of said housing.

5. A machine of the class described including a housing providing a tank adapted to contain a liquid and providing a hood over said tank, a wheel mounted for rotatable movement through said tank and said hood, supporting means for said wheel including a rotatable shaft member, a plurality of baskets mounted for swinging movement on said wheel and rotatable therewith, means for pivotally mounting said baskets on said wheel, a housing mounted on said tank below said outlet opening and providing a trough, a table extending angularly downward from said outlet opening and supported on said trough, a shelf slidably mounted on said table, and adapted to project into said housing through said outlet opening, said housing having an opening formed therein below said outlet opening and communicating with said trough, said table having openings formed therein communicating with said trough whereby liquid carried onto said table may be returned to said tank.

6. In steel tempering apparatus, a housing adapted to contain a liquid bath, a wheel rotatable in said housing, a plurality of radially arranged pivotally mounted baskets carried by said wheel for carrying articles through said bath, a trip for the baskets, a stationary table onto which the articles may be discharged from the baskets by said trip and fed by gravity therefrom, and means for drawing the liquid carried by the articles onto said table back into the housing.

7. In steel tempering apparatus, a housing adapted to contain a liquid bath, a wheel rotatable in said housing, a plurality of radially arranged pivotally mounted baskets carried by said wheel for carrying articles through said bath, a trip for the baskets, a stationary table onto which the articles may be discharged from the baskets by said trip and fed by gravity therefrom, means for drawing the liquid carried by the articles onto said table back into the housing, said table including a slideable shelf adapted to be extended above the trip for the reception of the articles dumped from the baskets.

8. In apparatus of the character described, a tank adapted to contain a bath, an article feed table substantially at the upper level of said tank and an article receiving table substantially at the upper level of the tank but opposite the latter from the feed table, said receiving table including a portion projecting into the tank, a wheel rotatable in the tank, and a plurality of pivotally mounted baskets radially arranged on the wheel for carrying articles fed into the baskets from said feed table, through the bath, to said receiving table, and a trip projecting into the tank below said portion in the path of movement of

the baskets, said trip dumping the baskets and discharging the articles therefrom onto said receiving table portion.

In testimony whereof I affix my signature.

OSCAR P. ANDERSON.
